UNITED STATES PATENT OFFICE

172,479

CANDELABRA

Rita Reid, New York, N. Y.

Application April 29, 1953, Serial No. 24,748

Term of patent 3½ years

(Cl. D48—2)

To all whom it may concern:

Be it known that I, Rita Reid, have invented a new, original, and ornamental Design for a Candelabra, of which the following is a specification, reference being had to the accompanying drawing, forming a part hereof.

The single figure is a perspective view of a candelabra showing my new design.

I claim:

The ornamental design for a candelabra, as shown.

No references cited.
